UNITED STATES PATENT OFFICE

136,058

DESIGN FOR A BRIC-A-BRAC OR THE LIKE

Alexander Vero, Bronx, N. Y.

Application February 12, 1942, Serial No. 105,779

Term of patent 3½ years

To all whom it may concern:

Be it known that I, Alexander Vero, a citizen of Czechoslovakia, residing at 1041 Findlay Avenue, Bronx, N. Y., in the county of Bronx and State of New York, have invented a new, original, and ornamental Design for a Bric-A-Brac or the like, of which the following is a specification, reference being had to the accompanying drawing, forming a part thereof.

In the drawing:

Fig. 1 is a front elevation of a bric-a-brac or the like, showing my novel design;

Fig. 2 is a side elevation, and

Fig. 3 is a rear view, each on a smaller scale.

The essential features of my design reside in the specific arrangement of the flags on the globe, the globe being relatively larger than the supporting rectangular base member.

I claim:

The ornamental design for a bric-a-brac or the like, as shown and described.

ALEXANDER VERO.
